UNITED STATES PATENT OFFICE.

ROBERT MUELLER, OF DECATUR, ILLINOIS, ASSIGNOR TO H. MUELLER MFG. CO., OF
DECATUR, ILLINOIS, A CORPORATION OF ILLINOIS.

DESIGN FOR A HOSE-WASHER.

48,004.

Specification for Design.

Patented Oct. 19, 1915.

Application filed August 5, 1914. Serial No. 855,332. Term of patent 14 years.

To all whom it may concern:

Be it known that I, ROBERT MUELLER, a citizen of the United States, residing at Decatur, in the county of Macon and State of Illinois, have invented a new, original, and ornamental Design for Hose-Washers, of which the following is a specification, reference being had to the accompanying drawing, forming part thereof.

In the drawing Figure 1 is a top plan

view of the washer; Fig. 2 is a side elevation of the same; and Fig. 3 is a bottom plan view thereof.

I claim:

The ornamental design for a hose washer, as shown.

ROBERT MUELLER.

Witnesses:

MABEL MCINTYRE,

CHARLES G. AUER.
